METHOD OF AND APPARATUS FOR THE DISTILLATION OF CARBONACEOUS MATERIAL

Filed March 15, 1924

UNITED STATES PATENT OFFICE

OTTO H. HERTEL, OF CHICAGO, ILLINOIS

METHOD OF AND APPARATUS FOR THE DISTILLATION OF CARBONACEOUS MATERIAL

Application filed March 15, 1924. Serial No. 699,402.

The invention relates generally to a method of and apparatus for driving off the volatile matter in coal and other carbonaceous material. The object of the invention, generally stated, is to deliver to the charge a relatively large amount of heat in a relatively short period of time without raising the charge or the evolved gases to a high temperature.

The quality and character of the gases evolved in the coking of coal depend considerably upon the temperature at which the operation is conducted and the duration of the heating. To obtain the most desirable coke and gas, continued overheating or local superheating of the charge must be avoided, since it results in excessive decomposition and in the formation of undesirable compounds as well as giving a variable composition to the gases. Superheating of gases in vertical retorts is generally less than in other types of retorts or ovens because the gases pass up centrally through the charge and are therefore partially protected from the heated external walls of the retort. Superheating, however, is not entirely obviated, since there is considerable impedance to the upflow of the gases due to their slow and tortuous passage through the mass of heated coke or coal.

An important object of the invention therefore is to provide a vertical retort in which the gases may be quickly removed therefrom and in which the gases near the outer heated walls may be quickly drawn away toward the center of the retort and thence removed directly into the gas main.

Heretofore it has been proposed to withdraw the gases through a central passageway or conduit built into the retort. The means for doing this have been variously applied in different forms of hollow members forming the conduit into which the gases were received through suitable openings. Such a conduit, however, is subject to fouling by the accumulation of tar and carbon within the tube itself and within the openings thereof.

A further object of this invention is to form or create a gas passage of which the charge itself constitutes the walls, the interstices of the charge being the openings through which the gases enter the passageway. By such a

method, fouling is prevented, and the walls are being constantly renewed with each new charge of coal into the retort.

A further object is to provide a vertical retort comprising mechanical means for creating and maintaining the gas passage through the charge.

In using such a mechanical means located within the charge, the same would ordinarily be subject to fouling in much the same manner as the walls of the perforated tube of prior devices. It is therefore a further object of my invention to provide means for heating said mechanical passage-forming means to destroy the fouling matter thereon.

It is a further and very important object of the invention to utilize the heated mechanical means as an internal source of heat to supplement the external heating of the charge whereby the time of heating a given charge is materially shortened.

A still further object is to apply the heat internally of the charge by means of a heated surface moving in contact with the material, whereby a relatively great amount of heat is delivered to the charge without raising the temperature above the desired point.

A further object of the invention is to subject the charge to vertical and lateral pressure during the distillation process to improve the quality of the coke thus produced.

Still another object is to provide coating means at each end of the retort for effecting a discharge of coke therefrom.

An apparatus embodying my invention is shown in the accompanying drawings in which—

Figure 1 is a longitudinal vertical section of the retort.

Fig. 2 is a cross section along the line 2—2 of Fig. 1, showing the arrangement of the parts within the retort proper.

Fig. 3 is a fragmentary longitudinal section of the retort taken along line 3—3 of Fig. 2.

Fig. 4 is a detail view of a heated tubular member which produces the passageway through the retort, showing also one type of heating means therefor.

Figs. 5, 6 and 7 show modified or alternative forms of the passage-forming means.

Fig. 8 is a cross-section of a retort having a single passage forming element.

Fig. 9 is a detail cross-section along line 9-9 of Fig. 1.

The vertical retort 10 is relatively narrow in one direction, say, twelve to eighteen inches in width and of a height suitable for the 10 character of the coke desired. It may be indefinitely extended horizontally by increasing the size of the retort and adding more passage-forming elements. However, it is to be understood that a plurality of passage-forming elements of the type to be hereinafter 15 described is not essential to the invention, and that a single one as shown in Fig. 8 may be employed which would preferably be used in a retort substantially circular in cross-section.

20 The retort 10 has a slight taper inwardly toward the top to facilitate the discharge of coke downwardly. It comprises at the lower end, a discharging mechanism; at the upper end, a feeding means and a gas chamber serving also as an expansion chamber for the charge; and an intermediate heating zone wherein the distillation takes place. Disposed centrally between the side faces of the 25 retort is one or more of the requisite passage-forming elements which in the form disclosed 30 pass through the retort lengthwise from end to end.

Suitable means may surround the heating 35 zone for the proper application of heat to the retort. It will be understood that the present invention is independent of the particular kind of fuel employed, and that coal, breeze, oil or any other fuel may be used, as desired. In the embodiment illustrated in the drawings, a heating chamber 12 surrounds the 40 retort in the heated zone, suitable brickwork 13 being provided for the purpose. Heat is supplied to the retort by the introduction of fuel in the form of gas through admission ports such as 14, 15, 16 and 17 suitably disposed in the brickwork laterally and vertically to 45 secure the best distribution of heat to the retort. Chimney outlets such as 18 are provided in the walls near the top of the oven to conduct 50 away the gaseous combustion products.

In starting the heating means, explosions frequently result due to the sudden ignition of residual gases remaining in the heated chamber from the previous operation. To 55 release the excessive pressure due to these explosions venting tubes 19 which are closed at their outer ends by safety valves or covers 20 extend through the walls 13. In the present instance I have shown two such passages in different positions, the upper one being inclined outwardly and upwardly.

The brickwork 13 is herein shown as supported on I-beams 21 running lengthwise under the retort. The retort 10 at the bottom 60 has a horizontal flange 22 resting on the

I-beams and at the top a horizontal flange 23 resting on the brickwork in a manner to close off the heating chamber 12. The extreme lower end of the retort 10 is flared outwardly along its length by an integral or added extension 24 at each side, suitable flanges 25 being provided thereon for supporting attachment to the I-beams. Each of the extensions 24 constitutes one side of a discharge chute 26, the end of which is closed by a tightly fitting trap door 27. The under sides 28 of each chute are integrally associated with a bottomless box-like structure having vertical sides 29, which structure constitutes part of a water seal for the retort more particularly described 70 75 80 hereinafter.

The feeding device for the retort may be of any suitable form properly provided with sealing means. Herein I employ a feeding hopper 30 at the top of the retort 10 above the flange 23, the hopper extending laterally away from the retort on one side thereof. A trap door 31, suitably sealed in the closed position, is shown through which the charge is introduced by suitable means (not shown). An upwardly tapering weight or bell 32 is movable up and down within the retort, the bell being shown in charging position in full lines in Fig. 1. The granular or powdered coal being charged into the retort is compelled to pass down through the relatively narrow space between the bell and the retort walls in the form of a thin stream or layer which in falling exposes the grains and small lumps of coal to the hot air within the retort, thus causing 90 a rapid and uniform heating of the coal before the same is deposited at rest, which substantially reduces the time consumed in distilling the charge. When the retort is fully charged, the bell is lowered onto or pressed against the material by suitable means. Herein I have provided connecting rods 34 from the bell 32 extending through the end of the retort to a controlling device. A hydraulic cylinder 35 is used to control the motion of the bell through suitable valves (not shown), the rods 34 being combined to work in unison with the piston rod 36 of the hydraulic piston and cylinder unit. By this means the bell can be raised or lowered as well as adjusted to resist 100 105 110 yieldingly the pressure of the swelling charge. A further use of this device is made at the end of the operation when the bottom is opened to start the charge downwardly out of the retort. The two discharge chutes above described necessitate a division of the charge into two portions. Because of the gas passageways which have been produced in the charge by means yet to be described, the charge is not solid along the required division line but is connected by the material between adjacent gas passages and at the side ends of the retort.

In order to facilitate discharge by aiding in the division of the two sections, separating 115 120 125 130

members may, if desired, be disposed within the retort to lie between the passageways. In the present instance, I have shown cruciform bars 37, each of which is suspended from a cross piece 38 at the upper end of the retort.

5 The blades of the cruciform bars 37 constitute knife edges to divide the charge. The adherence of the coke to the blades is broken by the pressure exerted by the bell 32 to effect the discharge thereof. Suitable holes are provided in the bell 32 to permit the motion of the same longitudinally of the bars. The suspension 39 of the bars from the cross piece and the guiding action of the bell 32, keep 10 the bars vertically disposed within the retort.

15 Suitable means are provided for the conduction of the gases away from the retort and for the sealing of the retort against leakage of the gas. The gas liberated by the process 20 is led from the retort by a pipe 40 into a hydraulic gas main 41. A valved vent pipe 42 leads to the atmosphere from the pipe 40. The upper part of the retort 10 is closed by the top 43 through which extends the mechanical 25 passage-forming means.

The mechanical means to create the gas passage in the charge may assume a variety of forms, but herein I have chosen to illustrate a rotatable member of non-circular cross- 30 section hereinafter referred to as a rotor. A twelve inch retort would have a rotor of approximately four and one-half inches as its transverse dimension. In the case of an eighteen-inch retort, the rotor would be about 35 eight inches in its transverse dimension. The rotor may extend through the retort from end to end, being supported externally of the retort in the present instance. In Fig. 2 a plurality of rotors is designated by the 40 numeral 44, each having a cross-section which may be described as produced by the flattening of a tubular member. The flattening of the tubular member illustrated is confined to a portion of the rotor's length which ex- 45 tends from just above the bottom of the retort to a point opposite the feeding hopper 30. If desired, the rotor may be of the cross- sectional form shown in Figs. 5 and 6 or it may be of any other suitable form. The portion 50 of the rotor which is within the retort, proper, may be cylindrical (as shown in Fig. 7) and may be mounted for rotation upon an eccentric axis α .

In the hollow member 44 of Fig. 1 there is 55 shown heating means comprising an arrangement of gas burners. In Fig. 4 these are designated by the numerals 45, 46 and 47 each burner having its own supply pipe 48 with an independent valve control 49. The burners are 60 preferably constructed in a spiral form like a triple threaded screen, as illustrated. The use of gas burners within the hollow rotor may make it desirable to provide the rotor with a lining 50 of metal adapted to resist 65 corrosion or oxidation (see Fig. 4).

The construction herein employed for each rotor necessitates a guide bearing at the bottom of the retort and a gas-tight closure associated therewith. Each such bearing and the retort closure are herein illustrated as 70 associated with the discharge chutes 26 into a common arrangement providing the water seal hereinbefore mentioned. The rotor 44 at its lower end rests upon a supporting annular base 51 through which enter the fuel 75 pipes 48. An antifriction thrust bearing support of suitable form is provided as illustrated by the numeral 52. Each rotor extends upwardly through the space between the vertical sides 29 of the bottomless box structure 80 hereinbefore described. Between the sides 29 is vertically-slidable a structure having an upper side 53 of inverted V-shape which constitutes the bottom of the retort. In the discharging position of the retort bottom, the 85 sloping sides 53 are alined with the plates 28, and serve to divide the charge into two portions. The retort bottom comprises vertical sides 54 which are vertically slidable between the sides 29. Along the ridge of the retort 90 bottom are openings for the rotors 44. Said openings have tubular extensions or sleeves 55 surrounding the rotors and extending downwardly toward the base 51, where they terminate by junction with the bottom 56 of a box trough 57, the sides of which extend upwardly outside of the box sides 29. The retort bottom and the trough thus become a unitary structure which is arranged to be 95 slidable longitudinally of the rotors. Suitable means are provided to control the movements of this unit, said means being herein shown as comprising control rods 58 secured to the yoke 59 which is operated by a hydraulic cylinder (not shown).

In the drawings the retort bottom is shown in full lines in its lowermost position and in operative relation to the discharge chutes 26. In the dotted-line position it is indicated in its uppermost position to close the lower end 110 of the retort. The joint at the point 60 need not be particularly tight, since the lower structure already described constitutes a water seal against leakage of gas from the bottom. The trough 57 is adapted to contain water which in the upper position of the retort bottom acts as a seal to prevent the escape of 115 gases between the plates 29 and 54. The escape of gases through the sleeve 55 about each rotor is prevented by the provision of a suitable stuffing box 61. The rotor at its upper end has a suitable gas tight bearing in the top 43 at the point 62.

A gear 63 rigid with the rotor has a thrust bearing support on a fixed member 64. Suitable power means for driving each rotor may be supplied in any well known manner, as for example, by means of a drive shaft 65 and bevel gear 66.

A fixed elbow 67 leading to a stack by pipe 130

68 has a relatively gas-tight bearing about the end of the rotor to conduct away the combustion gases from the burners within the rotor.

6 In the type of retort herein described the coal is admitted at the top to charge the retort completely, after which the retort is sealed and the distillation process carried out. As the coal becomes heated and the gases begin 10 to evolve, the mass swells which results in expansion upwardly toward the top of the retort. The weight 32 is operable to resist 15 yieldingly the upward expansion to any desired degree in order to give a more nearly uniform structure to the coke throughout the length of the retort. Without such a resistant device, the material in the bottom of the retort will form a denser coke than the material in the upper part of the retort, since the 20 weight of the material is most effective upon the lower portion of the charge. Consequently, by providing an additional weight to the charge which will act upon the upper portion in a yielding manner, I impose upon 25 the upper portion the conditions which ordinarily obtain at the bottom and therefore produce a more nearly uniform product in a single charge.

30 As the gases are evolved and the mass becomes plastic through heating, it ordinarily becomes more difficult for the gas to escape from within the mass to the receiving chamber provided therefor, but in a retort embodying the present invention the rotors 44 35 produce vertical passageways throughout the charge.

40 As the mass becomes plastic and pliable it tends to flow into the passageway to close it up. The rotation of the rotor is sufficiently fast to prevent this, and in thus preventing the inward flow of the material the rotor exerts a pressure thereon laterally with respect to the retort which gives a desirable density and hardness to the coke. The heat 45 which is applied to the rotor is sufficiently great to destroy any tarry products which may collect thereon during the distillation process, such destruction possibly leaving thereon a coating of coke or carbon. This 50 coating, however, is not accumulative, because in the charging of the apparatus the granular material will lie closely against this member and the mechanical scraping which results at the beginning of the process will effectively remove such carbon layer.

55 The rotor serves to distribute heat to the charge, thus shortening the coking operation without danger of local or excessive over-heating.

60 When the distillation process has been completed as far as desired, which may be determined by suitably testing by the character of the gases collected at the valved outlet 42, the retort is opened by lowering the bottom 65 to the position shown in full lines in Fig.

1. Simultaneously or thereafter the bell 32 is moved downwardly a short distance by the hydraulic cylinder 35 to release the coke from the retort walls and eject it from the retort through the chutes 26.

70 By forming a passage through the center of the charge, the coking process is shortened since the thickness of the charge is greatly reduced and the heating surface is increased. Being quickly conducted away from the hot 75 zones, the gases are not subjected to detrimental heating, the quality of the coke is improved, and the rate at which coking proceeds is increased.

80 As the eccentric or non-circular tube revolves the coal will follow the travel of the eccentric portion or portions of the tube, that is to say, the coal will move to fill the constantly shifting gas passage, until the stage where the coal becomes plastic is reached. 85 Such movement of the coal is desirable, as it diffuses the heat through the mass. The friction among the solid particles likewise conduces to the heating of the charge. Moreover, the rubbing action of the tube accelerates the delivery of the heat into the mass.

90 When the mass begins to set, there is less and less tendency to close in around the rotor, and thus the delivery of heat to the mass from the rotor is self-regulating, the amount of heat supplied to the mass from the rotor being automatically reduced as the need for the application of heat diminishes.

95 In the coking of coal exothermic reactions set in at about 350° C. I deem it desirable, 100 as regards economy of operation, character of by-products and quality of coke, to make use of the exothermic reactions to the greatest practicable extent in the distillation of the coal. In other words, I aim to avoid the creation of conditions under which endothermic 105 reactions occur. For this reason I prefer to maintain outside the retort and within the rotor a temperature of approximately 500° C.—at least until the exothermic reactions 110 have commenced.

115 The apparatus and certain features of the process herein disclosed are highly advantageous in the distillation of carbonaceous material, whether the product chiefly sought be coke, gas or oils.

120 I believe myself to be the first to provide practical means for agitating a charge of coal undergoing distillation. By reason of the agitation to which the coal is subjected in an apparatus embodying my invention, heat is rapidly and uniformly disseminated throughout the charge, and the entire mass quickly raised to the desired temperature.

125 I also believe that I am the first to distill a batch or unit mass of carbonaceous material in a retort containing a plurality of internally heated tubes for rapidly heating the entire batch to the desired temperature,

and aim to claim such an apparatus broadly in certain of the following claims.

I claim as my invention:

1. An apparatus for the distillation of carbonaceous material comprising, in combination, a vertical retort adapted to contain a charge of such material, means for heating the retort, a plurality of means for creating a plurality of vertical gas passages in the retort, separating blades vertically disposed between adjacent passage-creating means, a bottom for the retort movable away therefrom, means to push the finished charge downwardly in the retort, whereby the adherence of the charge to the retort walls and the blades may be broken, and discharge chutes below the retort and extending from opposite sides thereof, said blades and passage-creating means being arranged substantially to divide the charge into half portions, one for each discharge chute. 70
2. An apparatus for the distillation of carbonaceous material comprising, in combination, a vertical retort adapted to contain a charge of such material, means for heating the retort, means for creating a plurality of vertical gas passages in the retort, a bottom for the retort, said bottom being of inverted V-form to divide the material when said bottom is lowered for removal of said material, means to move said bottom vertically, and means to push the finished charge downwardly onto the lowered bottom to split the charge into two portions along the line of the vertical passages therein. 80
3. An apparatus for the distillation of carbonaceous material comprising, in combination, a vertical retort adapted to contain a charge of such material, heating means for said retort, means for creating a plurality of laterally aligned vertical gas passages through the charge, and means movable vertically in said retort at the lower portion thereof, and adapted for separating the charge into two portions along the line of said aligned passages. 90
4. An apparatus for the distillation of carbonaceous material comprising, in combination, a vertical retort adapted to contain a charge of such material, heating means for said retort, revolving means extending vertically through said retort for creating a plurality of laterally aligned gas passages through the charge, and means movable vertically in said retort at the lower portion thereof, and adapted for dividing the charge along the line of said passages. 100
5. An apparatus for the distillation of solid carbonaceous material and production of coke having, in combination, a vertical retort adapted to contain a charge of such material, means for heating the outer surface of said retort, a non-conveying member extending vertically through said retort, heating means associated with said member for heating the interior of said retort, means for moving said member in a fixed path within said retort from one position to another to create a relatively straight longitudinally gas passage through the charge and means for permitting the removal of the resulting batch of coke from said retort. 110
6. An apparatus for the distillation of carbonaceous material comprising, in combination, a vertical retort adapted to contain a charge of such material, a revolvable member extending longitudinally through said retort and adapted to be revolved on a longitudinal axis and upon being revolved to create a gas passage vertically through the charge, means for closing the lower end of said retort, means for heating said retort, an annular weight fitting around said member and disposed in the upper end of said retort, said weight being adapted to rest upon the charge to more nearly equalize the pressure throughout said charge, and being adapted to be lowered to remove said charge, and means for actuating said weight. 120
7. An apparatus for the distillation of carbonaceous material comprising, in combination, a vertical retort having a feeding hopper at its upper end and being adapted to contain a charge of such material, means for closing the lower end of said retort, means for heating said retort, an upwardly tapering weight member centrally disposed in the upper end of said retort below said feeding hopper, said weight member being slightly less in dimension than said retort to define therewith a narrow peripheral passage through which a charge may be passed into said retort, and means for supporting said weight member. 130
8. An apparatus for the distillation of carbonaceous material comprising, in combination, a vertical retort adapted to contain a charge of such material, a plurality of consecutively arranged laterally spaced members adapted upon rotation to create a plurality of vertical gas passages through the charge, means for rotating said members on a vertical axis, a plurality of laterally spaced auxiliary members between said rotary members, said rotary members and said auxiliary members being adapted to substantially separate said charge into two parts, and means for heating said retort. 140
9. An apparatus for the distillation of carbonaceous material comprising, in combination, a vertical retort adapted to contain a charge of such material, a plurality of consecutively arranged laterally spaced vertical members extending centrally through said retort, means for closing the lower end of said retort to retain the charge therein, a weight member having a plurality of openings fitting respectively over said members and being adapted to rest upon said charge to equalize the pressure thereof and to resist expansion 150

thereof, and means for lowering said weight to remove said charge when said retort is open.

10. An apparatus for the distillation of 5 carbonaceous material comprising, in combination, a vertical retort adapted to contain a charge of such material, the lower end of said retort being formed with divergent discharge chutes, a closure having an inverted V-shaped upper end in the lower end of said retort movable vertically to open or close said discharge chutes, the inclined sides of said inverted V-shaped end having the same slope as the walls of said discharge chutes, and 15 means extending vertically through said retort adapted to divide the charge in line with the apex of said closure.

11. An apparatus for the distillation of solid carbonaceous material to form coke, 20 comprising, in combination, a vertical retort adapted to contain a charge of such material, a vertical member extending longitudinally through said retort and rotatable on a vertical axis and being adapted upon rotation to 25 create a passage through the charge, means for heating the exterior of said retort, and heating means within said member adapted to heat the latter to heat the interior of the material.

30 12. An apparatus for the distillation of carbonaceous material comprising, in combination, a vertical retort adapted to contain a charge of such material, a plurality of laterally spaced members extending longitudinally through said retort and substantially dividing the interior of said retort into two parts, a closure movable in the lower end of said retort, the inner end of which is inverted V-shaped with the apex in line with said 35 members, and means for heating said retort.

13. An apparatus for the distillation of carbonaceous material comprising, in combination, a vertical retort adapted to contain a charge of such material, the lower end of said 45 retort being formed with two diametrically opposed discharge chutes, said discharge chutes having a central downwardly extending sleeve at their junction, a rotatable member extending through said sleeve and vertically through said retort, said member being 50 shaped to create upon rotation a path centrally through the charge in said retort, a closure movable in said sleeve and adapted to open and close said discharge chutes, said 55 closure having a central sleeve embracing said member, and an outer sleeve attached to and disposed in spaced relation about said first mentioned sleeve, and adapted to provide means for a liquid seal in the lower end of 60 said closure.

14. An apparatus for the distillation of solid carbonaceous material and production of coke comprising, in combination, a vertical retort, means for admitting a batch of such 65 material to the top of said retort, a removable

closure for the bottom of said retort for confining said batch in said retort, a non-conveying member extending vertically through said retort, said member being mounted for lateral recurrent movement and adapted upon such movement to form a vertical gas passage through said batch, means for actuating said member, means for heating said retort, and means for opening said closure to remove coke from said retort.

15. An apparatus for the distillation of solid carbonaceous material and production of coke comprising, in combination, a vertical retort, means for admitting a batch of such material to the top of said retort, a removable closure for the bottom of said retort for confining said batch in said retort, a hollow non-conveying member extending vertically through said retort and mounted for lateral recurrent movement about a vertical axis, said member having a substantially straight longitudinal and laterally offset portion adapted upon said movement to exert a wiping action on the interior of said batch and thereby to form a relatively straight vertical gas passage through said batch, means for actuating said member, means for heating said retort, means for heating the interior of said member, and means for opening said closure to remove coke from said retort.

16. An apparatus for the distillation of solid carbonaceous material and production of coke comprising, in combination, a vertical retort, means for admitting a batch of such material to the top of said retort, a removable closure for the bottom of said retort for confining said batch in said retort, a non-conveying member extending vertically through said retort, said member being mounted for lateral recurrent movement and adapted upon such movement to form a vertical gas passage through said batch, means for actuating said member, a pressure member adjustably and yieldingly mounted in the upper end of said retort for resisting swelling of said batch, means for heating said retort, and means to open said closure to remove coke from said retort.

17. For use in a vertical retort having an inwardly spaced longitudinal core, the batch process of distilling and coking of granular carbonaceous material which will become plastic upon being heated to a predetermined temperature, comprising feeding a batch of said material into the top of said retort and confining said batch in a hollow vertical column defined by said retort and said core, creating a vertical gas passage through said batch along the exterior of said core, applying heat to said batch from within said passage, agitating said batch while in granular form, applying mechanical pressure to said batch from within said passage while said batch is plastic, and removing the coked batch from the bottom of said retort.

18. For use in a vertical retort having an inwardly spaced longitudinal core, the batch process of distilling and coking granular carbonaceous material which will become plastic upon being heated to a predetermined temperature, comprising feeding a batch of said material into the top of said retort and confining said batch in a hollow vertical column defined by said retort and said core, creating a relatively straight vertical gas passage through said batch along the exterior of said core, heating said batch, applying mechanical pressure laterally to said batch from within said passage and vertically to the top of said batch while said batch is plastic, and removing the coked batch from the bottom of said retort. 70
19. For use in a vertical retort having an inwardly spaced longitudinal core, the batch process of distilling and coking granular carbonaceous material which will become plastic upon being heated to a predetermined temperature, comprising feeding a batch of said material into the top of said retort and confining said batch in a hollow vertical column defined by said retort and said core, creating an interior vertical gas passage through said batch along the exterior of said core, heating the outside of said column, applying heat to said batch from within said passage, applying a yielding pressure vertically to the top of said batch while said batch is plastic whereby swelling of said batch is resisted, and removing the coked batch from the bottom of said retort. 75
20. For use in a vertical retort having an inwardly spaced longitudinal core, the batch process of distilling and coking granular carbonaceous material which will become plastic upon being heated to a predetermined temperature, comprising feeding a batch of said material into the top of said retort and confining said batch in a hollow vertical column defined by said retort and said core, creating an interior vertical gas passage through said batch along the exterior of said core, heating the outside of said column, applying heat to said batch from within said passage, agitating said batch while in granular form, causing said batch to be substantially quiescent and applying mechanical pressure laterally thereto from within said passage when said batch is plastic, applying a yielding pressure vertically to the top of said batch while said batch is plastic whereby swelling of said batch is resisted, and removing the coked batch from the bottom of said retort. 80
21. For use in a vertical retort having an inwardly spaced longitudinal core, the batch process of distilling and coking granular carbonaceous material which will become plastic upon being heated to a predetermined temperature, comprising heating the exterior of said retort, feeding a batch of said material in a thin stream about said core into the top of said retort and confining said batch in a hollow vertical column defined by said retort and said core, creating a vertical gas passage through said batch along the exterior of said core, applying heat to said batch from within said passage, agitating said batch while in granular form, applying mechanical pressure to said batch from within said passage while said batch is plastic, and removing the coked batch from the bottom of said retort. 85

CERTIFICATE OF CORRECTION.

Patent No. 1,731,165.

Granted October 8, 1929, to

OTTO H. HERTEL.

It is hereby certified that error appears in the printed specification of the above numbered patent requiring correction as follows: Page 3, line 61, for the word "screen" read "screw"; page 5, line 69, claim 5, strike out the word "longitudinally" and insert the same after the word "passage" in line 70, same claim; page 7, line 52, claim 20, for the word "when" read "while"; and that the said Letters Patent should be read with these corrections therein that the same may conform to the record of the case in the Patent Office.

Signed and sealed this 26th day of November, A. D. 1929.

(Seal)

M. J. Moore,
Acting Commissioner of Patents.
